ATTORNEY.

flexible wristband, and particularly a wristband having a plurality of links, and having a means for readily adjusting the length of the band, comprising a flexible hollow member having a transverse partition, a pair of hollow second units, a pair of flexible first units, a pair of link-receiving compartments, a pair of latch-receiving compartments, and a clasp.

UNITED STATES PATENT OFFICE

2,635,315

ADJUSTABLE BAND FOR LADIES' WRIST WATCHES OR THE LIKE

Jack L. Kaufman, New York, N. Y.

Application April 21, 1951, Serial No. 222,229

4 Claims.

(Cl. 24—206)

1

This invention relates to bands for ladies wrist-watches or the like, and more particularly to such bands that are readily adjustable in length.

A primary object of the invention is to provide an adjustable band for a lady's wristwatch, a bracelet or the like, that has incorporated therein simplified and improved features of construction.

Another object of the invention is to provide a band of the character indicated with adjustable means, whereby the effective length of the band may be readily and quickly varied by the user without the use of tools.

The invention has for a further object the provision of an adjustable band for a lady's wrist-watch or the like that is attractive in design, that is simple and sturdy in construction, that is reasonable in manufacturing cost, and that is adapted to perform its intended functions in an efficient and dependable manner.

To the end that the foregoing objects may be attained, an adjustable band constructed in accordance with this invention preferably comprises a pair of units, namely, a first unit and a second unit. The first unit includes a plurality of links connected in series with the aid of suitable coupling elements. Each link has a bottom opening. The second unit comprises a hollow member closed at one end and open at its other end. A partition is disposed across the interior of the hollow member and divides the same into a link-receiving compartment and a latch-receiving compartment. The hollow member has a bottom aperture that communicates with both compartments. A latch plate is pivotally connected to one end of the hollow member, preferably the open end, and constitutes at least a portion of the bottom wall of the hollow member. This plate carries a latch that is adapted to project into the latch-receiving compartment when the plate is in closed position. The latch has a hook element at its free end that engages a recess formed in the partition, whereby to maintain the plate in closed position. A pin is carried by and projects upwardly from the plate and is adapted to register with the opening in the bottom of a link upon insertion of an end of the first unit into the hollow member through the open end thereof.

The link-receiving compartment is of sufficient length to accommodate two or more of the links of the first unit. The parts are so arranged that the pin carried by the plate may register with the opening in either the end link or the next adjacent link, depending upon the extent to which

the first unit is inserted in the hollow member. The plate has an extension or tab at its end, remote from its pivotal connection with the hollow member, to facilitate disengagement of the latch from the hollow member and thereby permit swinging the plate into open position.

The enumerated objects, together with other objects and the advantages of this invention will be readily apparent to persons skilled in the art upon reference to the detailed description that follows and the annexed drawing which respectively describe and illustrate a band construction for a lady's wristwatch embodying the invention.

In the drawing:

15 Figure 1 is a top plan view of a portion of a preferred and recommended watch band constructed in accordance with the invention;

Figure 2 is a view in enlargement taken along line 2—2 of Figure 1;

Figure 3 is a bottom plan view of Figure 2;

Figure 4 is a view taken along line 4—4 of Figure 2;

Figure 5 is a view taken along line 5—5 of Figure 2; and

Figure 6 corresponds to a portion of Figure 2, parts being omitted and other parts being shown in another relative position.

Referring now to the drawing, I have illustrated therein a band for a lady's wristwatch or the like comprising a pair of flexible first units 10, a pair of hollow second units 11, each of which is removably connected to a corresponding first unit 10, and a clasp 12 that connects units 11 together. This clasp may be of any known form of construction.

35 As is best shown in Figures 2 and 3, each flexible unit 10 includes a plurality of links 13 that are connected in series by couplers 14. Each link 13 may carry a gem, such as a cut diamond 15, and is open at the bottom as indicated at 16.

40 Each second unit 11 preferably comprises a hollow member 17 having a top wall 18, that also carries decorative gems 15, and a pair of spaced side walls 20 that have inwardly extending lateral flanges 21 which are spaced apart to define an opening 22. The hollow member is additionally provided with an end wall 23 that is connected to clasp 12. The other end of hollow member 17 is open, as indicated at 24. A transverse partition

45 25 divides the interior of hollow member 17 into a link-receiving compartment 26 and a latch-receiving compartment 27, both of which compartments communicate with opening 22. Link-receiving compartment 26 is of sufficient size to accommodate a plurality of links 13 and in the

illustrated construction is adapted to receive two such links. Partition 25 is notched or recessed as indicated at 28.

A latch plate 30 that constitutes a part of the bottom wall of hollow member 17 has an up-standing pin or lug 31 and a resilient latch 32 that terminates in a hook element 33. Pin 31 and latch 32 may be formed integral with plate 30 as shown, or may be separate elements rigidly secured to the plate, by welding or in any other desired manner known to the art. Plate 30 is pivotally connected to the open end of hollow member 17 by a pin or the like 34. Plate 30 has an extension or tab 35 that projects beyond end wall 23 when the parts are in the relative position shown in Figures 2 and 3 to facilitate swinging plate 30 in a clockwise direction about pivot pin 34, as viewed in Figure 2.

For the purpose of outlining the operation of the illustrated embodiment of the invention, it is assumed that the parts are in the relative position shown in Figure 2. With the parts so arranged, the end link 13 of unit 10 is disposed within hollow member 17. Plate 30 is in closed position so that hook element 33 of latch 32 registers with notch 28 in partition 25, thereby maintaining the plate in closed position. Also, pin 31 registers with opening 16 in link 13 and thus effects coupling engagement between units 10 and 11.

Unit 10 may be released from unit 11 by first gripping plate extension 35, then urging the plate in a clockwise direction about pin 34 to effect disengagement of latch hook element 33 from notch 28 and finally swinging pin 31 out of registry with opening 16 in the end link.

If it is desired to decrease the effective length of the band, the end portion of unit 10 may be inserted into hollow member 17 so that two of its links 13 are positioned therewithin. The latch plate is then swung to closed position, whereby its pin 31 registers with bottom opening 16 in the second link and latch 32 re-engages the notch in partition 25.

From the foregoing, it is believed that the construction, operation and advantages of my present invention will be readily comprehended by persons skilled in the art. It is to be clearly understood, however, that various changes in the apparatus set forth above may be made without departing from the scope of the invention, it being intended that all matter contained in the description or shown in the drawing shall be interpreted as illustrative only and not in a limiting sense.

I claim:

1. In a device for varying the effective length of a wristwatch band or the like that includes a flexible section consisting of a plurality of series-connected links that are provided with bottom openings, the combination comprising a hollow member closed at one end and open at the other end, a partition across the interior of the hollow member and dividing the same into a link-receiving compartment and a latch-receiving compartment, said hollow member having a bottom aperture that communicates with both compartments, a plate pivotally connected to one end of the hollow member and constituting at least a portion of the bottom wall thereof, a latch carried by the plate, said latch projecting into the latch-receiving compartment and detachably engaging the partition, and a pin carried by the plate and projecting into the link-receiving compartment, said pin being adapted to register with a link opening upon insertion of a portion of the flexible section into the hollow member through the open end thereof to effect connection between the device and the flexible section.

2. A device in accordance with claim 1, wherein in the plate is pivotally connected to the open end of the hollow member and the pin is disposed intermediate the latch and the pivotal connection between the plate and the hollow member.

3. A device in accordance with claim 1, wherein in the latch is resilient and includes a hook element adapted to register with a recess formed in the partition.

4. A device in accordance with claim 1, wherein in the latch plate is pivotally connected to the open end of the hollow member, the pin is disposed intermediate the latch and the pivotal connection between the plate and the hollow member, and the latch is resilient and includes a hook element adapted to register with a recess formed in the partition.
